RETARDING DEVICE FOR SPRINKLER SYSTEM ALARMS

Filed June 8, 1927

FIG. 1.

FIG. 3.

FIG. 2.

INVENTOR:
WILLIAM B. GRIFFITH
BY F. DeWitt Goodwin

UNITED STATES PATENT OFFICE

WILLIAM B. GRIFFITH, OF AUDUBON, NEW JERSEY, ASSIGNOR TO STAR SPRINKLER CORPORATION, A CORPORATION OF NEW JERSEY

RETARDING DEVICE FOR SPRINKLER-SYSTEM ALARMS

Application filed June 8, 1927. Serial No. 197,294.

My invention relates to improvements in a retarding device for controlling alarm signals used in connection with automatic sprinkler systems for fire protection.

5 The object of my invention is to provide an efficient retarding device which is dependable and will operate under all conditions; a further object of my invention is to simplify the construction of the retarding device by 10 eliminating all springs and diaphragms which have a tendency to corrode and fail in operation; and a still further object of my invention is to provide a device which will permit the discharge of excess water which 15 passes through the main valve of the system due to variations in the water pressure and particularly to what is known as water-hammer. These together with various novel features of construction and arrangement of 20 the parts, which will be more fully herein-after described and claimed, constitute my invention.

Referring to the accompanying drawing, Fig. 1 is a central vertical sectional view of 25 my improved retarding device shown connected with a check valve and alarm devices; Fig. 2 is a vertical central sectional view of the retarding device drawn on a larger scale and showing the valve member in a different position; and Fig. 3 is a horizontal section on line 3—3, Fig. 2.

In the accompanying drawing, in which like reference characters refer to like parts, 1 represents the retarding device, comprising 35 the casing 2 and a base 3, detachably secured to the lower part of the casing. The base 3 is provided with an inlet connection 4 and a removable valve seat 5 associated with said inlet connection, through which latter water 40 is admitted to the casing 2 from the main valve 6 of the sprinkler system through a suitable connecting pipe 7. When the main valve clapper 8 is lifted off its seat 9, the annular recess 10, formed in the valve seat 9, 45 will be exposed, thus opening communication

through the pipe 7 with the retarding device 1.

The base 3 of the retarding device is also provided with an outlet port 12, having a removable valve seat 13. A valve member 15 50 is pivotally mounted upon a shaft 16, mounted in bearing lugs 17 located upon the base 3.

The valve member 15 is provided with two flat facing surfaces 18 and 19 forming valves 20 and 21. The valve 20 rests upon the valve 55 seat 5. The valve member 15 is provided with a weight 25 adapted to normally hold the valve 20 upon its seat 5 and hold the latter closed due to the overbalanced portion of the valve member carrying the valve 20. The 60

valve member 15 is also provided with a depending collar 27 which fits loosely over the sleeve forming the valve seat 5. Said collar forms a resistance to the water when flowing through the inlet connection 4, thus insuring 65 the lifting of valve 20 a sufficient distance off the valve seat 5 and imparting sufficient movement to the valve member 15 to insure the valve 21 closing upon its seat 13, thus closing the outlet port 12, causing the casing 2 to be 70

filled with water when a full flow is passing through the inlet connection 4. The valve 21 is provided with a small aperture 29 for the slow passage of water when the supply has been cut off by the closing of the main 75 valve 8, thus relieving the valve 21 of any pressure which would tend to hold it closed upon its seat and prevent the weight 25 from moving the valve member 15 into its normal position shown in Fig. 1.

The casing 2 is provided with an overflow connection 30 through which the water passes, when the casing 2 is full, to the circuit closing alarm device 31 and the water motor alarm device 32, which devices are well known 85 in the art and may be of any type.

The operation of my invention is as follows: The valve member 15 is normally held in the position shown in Fig. 1 by the overbalanced end of said member 15, so that water 90

will drain through the outlet port 12. When the main valve 8 is forced off its seat the water will flow into the casing 2, lifting the valve 20 off its seat 5 and moving the valve member 15 into a position for closing the valve 21 upon its seat 13, thus causing the casing 2 to be filled and operate the alarm devices 31 and 32. Should the valve 8 immediately close upon its seat, due to the sprinkler system not being open, the weighted end of the member 15 will open the valve 21 and allow the casing 2 to empty rapidly, so that the casing 2 will not be filled up entirely with water due to the successive opening of the valve 8, due to water hammering, thus insuring the alarm devices 31 and 32 remaining out of action unless the main valve is fully opened.

I claim:

20 1. A retarding device for a sprinkler system alarm, comprising, a casing having an inlet connection communicating with the sprinkler system, a connection at the lower portion of the casing forming an outlet port, an overflow connection upon the casing for actuating an alarm device, a bearing upon said casing located between said inlet connection and said outlet port, a lever pivotally mounted upon said bearing, said lever having 25 a portion normally positioned adjacent to said inlet connection, a cup shaped part upon said lever positioned concentrically with said inlet connection forming a resistance to water flowing through said inlet connection 30 when said lever is partially lifted from said inlet connection, and said lever having a portion normally located in spaced relation to the outlet port adapted to close said outlet port when the lever is moved by a flow of water through said inlet connection.

35 2. A retarding device for a sprinkler system alarm, comprising, a casing having an inlet connection and an outlet port, an overflow connection upon the casing for actuating an alarm device when the casing overflows, a valve member operatively mounted within the casing adapted to normally obstruct said inlet connection, a depending collar upon said member loosely surrounding the inlet connection, and a part upon said member normally positioned in spaced relation with said outlet port adapted to close the latter when said member is moved away from said inlet connection by a flow of water through the latter.

40 3. A retarding device for a sprinkler system alarm, comprising, a casing having an inlet connection communicating with the sprinkler system, a connection at the lower portion of the casing forming an outlet port, an overflow connection upon the casing for actuating an alarm device when the casing overflows, a base forming part of said casing, a lever pivotally mounted upon said base, a depending collar upon one arm of said

lever fitting loosely over the inner end of said inlet connection adapted to be moved away from said inlet connection by a flow of water through the latter, a part upon the opposite end of said lever adapted to close upon said outlet port, and a weight upon the arm of said lever located adjacent to said inlet port for normally holding the lever in spaced relation with the outlet port.

In testimony whereof I affix my signature.

WILLIAM B. GRIFFITH.
